(57) CLAIM

I claim, the ornamental design for an outsole for footwear, as shown and described.

DESCRIPTION

FIG. 1 is a front view of an outsole for footwear, showing my new design;

FIG. 2 is a rear view thereof;

FIG. 3 is a side view thereof;

FIG. 4 is an opposite side view thereof; and,

FIG. 5 is a plan view thereof.

Portions illustrated in broken lines show environment and form no part of the claimed design.
